United States Patent Office

Des. 198,343
Patented June 2, 1964

198,343

DISPLAY CASE FOR A LIGHTER OR SIMILAR ARTICLE

Philip Beck, New York, N.Y., assignor, by mesne assignments, to Jacques Kreisler Manufacturing Corporation, North Bergen, N.J., a corporation of New Jersey

Filed Nov. 27, 1963, Ser. No. 77,596

Term of patent 14 years

(Cl. D58—12)

FIG.1

FIG.4

FIG. 1 is a front elevational view of a display case for a lighter or similar article showing my new design.

FIG. 2 is a side elevational view thereof.

FIG. 3 is a perspective view thereof showing the case in open position.

FIG. 4 is a rear elevational view thereof.

I claim:

The ornamental design for a display case for a lighter or similar article, substantially as shown.
